UNITED STATES PATENT OFFICE.

JONAS HERLENIUS, OF BROOKLYN, NEW YORK, ASSIGNEE TO HAMILTON & HANSELL, INC., OF NEW YORK, N. Y., A CORPORATION OF NEW YORK.

ELECTRIC FURNACE.

1,338,631.

Specification of Letters Patent. Patented Apr. 27, 1920.

Application filed February 8, 1918. Serial No. 216,013.

To all whom it may concern:

Be it known that I, JONAS HERLENIUS, a subject of the King of Sweden, residing in the borough of Brooklyn, county of Kings, 5 and State of New York, have invented certain new and useful Improvements in Electric Furnaces, of which the following is a specification.

My invention relates to electric furnaces 10 and particularly to an improved mounting and feed mechanism for the furnace electrodes, the object of my invention being to provide a mounting such that the aperture through which the electrode projects into 15 the furnace may be sealed against air leakage without interfering with either the feeding or the tilting of the electrodes, and also to provide a feed mechanism of improved type.

20 In the accompanying illustrative drawings,

Figure 1 is a side elevation of an electric furnace in which my invention is embodied in one form;

25 Fig. 2 is a broken plan of one of the side electrode mountings; and

Fig. 3 is a vertical section through this mounting.

The furnace here shown is of the type 30 commonly known as the Rennerfelt furnace, the body 10 of which has a top opening for the entrance of a vertical electrode 11, and two side openings for oppositely disposed electrodes, only one of which, 12, is illustrated. The furnace is provided with a lateral pouring spout 13, and is supported on semi-circular bearing plates 14, which rest 35 on rolls 15 journaled in standards 16 on a masonry base 17. Inasmuch as the present 40 invention is particularly concerned with the mounting and feed of the side electrodes, it is unnecessary to go further into detail in regard to the general furnace construction. Moreover, since both of the side electrodes 45 are mounted and operated in the same manner, it suffices, for the sake of explanation, to show and describe one of these.

Referring to Figs. 2 and 3 where I have 50 illustrated, on a large scale, the mounting for the electrode 12, it will be seen that the latter is carried in a water-jacket sleeve 18, the flanges 19 on which register with coöperating flanges of a clamping bracket 20, secured thereto by the bolts 21. Integral with

the bracket 20 are electrode supporting arms 55 22, terminating in trunnions 23 journaled in bearing flanges 24 carried by a side plate 25, riveted to the shell of the furnace 10. This side plate 25 is apertured at 26, in register with a hole in the furnace wall, to permit the passage of the electrode 12 therethrough into the furnace chamber. Inasmuch as the electrode is tiltable, this aperture must have considerable clearance around the electrode to permit it to assume 60 its various angular positions. Ordinarily, considerable air leakage into the furnace chamber occurs at this point and constitutes an objectionable feature which has not hitherto been overcome, so far as I am 65 aware. I have provided a packing for the electrode at this point which prevents this air leakage, and at the same time, neither obstructs the angular movement of the electrodes nor their advance during the operation 70 of the furnace. As here shown, the packing 27 is in the form of a non-conducting, heat-resisting ring of any suitable material, such as asbestos fiber, which is held by retaining-ring 28 on the water-jacket 18 75 in a plane coinciding with the axis of the trunnions 23. The retaining-ring 28 may be secured to the plate 25 by screw bolts 29, so that it holds the packing in fixed position. Owing to the location of packing ring 27, 80 there is obviously little or no movement thereof when the electrode is tilted, and such yielding thereof as may be necessary to accommodate it to the swing of the electrode is taken up by the elasticity of the packing it- 85 self.

In order to feed the electrode forward into the furnace as it is consumed, I clamp thereto at 30 a rack 31, supported by slides 32-33 carried by a long spur 34 extending 90 outward in the direction of the length of the electrode from the lower portion of the water-cooled sleeve 18. Meshing with the rack 31 is a pinion 35 on the spindle 36, at the outer end of which is a worm wheel 37 95 engaged by the worm 38 on spur shaft 39 fast with the bevel pinion 40. The latter meshes with a coöperating bevel pinion 41 carried by spindle 42 driven through shaft 43 and universal couplings 44 from the electric motor 45 mounted on a bracket 46 secured to the furnace shell. The universal 100 couplings 44 make it possible to feed the

electrode 12 forward when the electrode is up-tilted as indicated in dotted lines in Fig. 3.

Instead of using a stationary motor with shaft and universal couplings as just described, the motor, if not too heavy, may be mounted directly on the spur 34 and geared to the pinion 35. This construction is preferred for small furnaces where the electrodes are somewhat lighter—and even for the large furnaces, when possible.

The motor 45, in either event, runs continuously during the operation of the furnace and provides a predetermined gradual feed of the electrodes into the furnace chamber. If desired, the speed of the motor may be controlled at will, through any suitable regulating device. In furnaces of automatic operation, a motor feed of the type described is a very desirable feature.

The top electrode 11 is clamped at 47 to a rack 48 which takes its motion from a pinion (not shown), operated through a worm gear 49 from the shaft 50 through the hand wheel 51.

The side electrodes are tilted on their trunnions 23 by means of a hand wheel 52 on screw rod 53 working in tapped bosses 54 on spur 34 and bearing, at its inner end, against the plate 25.

Various modifications in detail of construction will readily occur to those skilled in the art without departing, however, from what I claim as my invention.

35 I claim:

1. An electric furnace having an apertured side wall, an electrode projecting with clearance through the aperture in the side wall into the furnace chamber, a pivotal support for said electrode exterior to the furnace shell, and a flat packing ring surrounding said electrode substantially in the plane of the pivotal axis of the electrode support to prevent leakage of air into the furnace chamber through the electrode opening in the side wall thereof.

2. An electric furnace having an apertured side wall, an electrode projecting with clearance into the furnace chamber through the aperture in the side wall, a pivoted trunnion support for said electrode exterior to the furnace shell, a flat packing ring spaced from the electrode support and surrounding said electrode exterior to the furnace shell to prevent leakage of air into the furnace

chamber through the electrode opening, and a retaining device engaging said packing ring to hold the same in position.

3. An electric furnace having an apertured side wall, an electrode projecting with clearance into the furnace chamber through the apertured side wall, a water jacket surrounding said electrode and projecting into said aperture, a pivotal support in which said jacket is journaled to permit the angular displacement of the electrode within the furnace chamber, a flat packing ring engaging said water jacket at said aperture but spaced from the pivotal support and serving to prevent leakage of air into the furnace chamber through the electrode opening, together with a retaining device engaging said packing ring to hold the same in position.

4. An electric furnace having an apertured side wall, an electrode passing therethrough into the furnace chamber, and means for feeding said electrode into the furnace chamber, said means comprising a rack clamped to the electrode, a pinion meshing with the rack, an electric motor and an operative connection between the latter and the pinion for steadily advancing the electrode at predetermined speed.

5. An electric furnace having an apertured side wall, an electrode passing therethrough into the furnace chamber, and means for feeding said electrode into the furnace chamber, said means comprising a rack clamped to the electrode, a sleeve through which the electrode passes, a bracket on said sleeve and motor elements mounted on said bracket and operatively connected to said rack for advancing the electrode.

6. An electric furnace having a side electrode, a sleeve mounted thereon, a spur on said sleeve extending in the direction of the electrode length, and feed mechanism carried by said spur for advancing the electrode into the furnace as it is consumed.

7. An electric furnace having a tilting side electrode, a sleeve mounted thereon, a spur on said sleeve extending in the direction of the length of the electrode, and a screw rod mounted in said spur and bearing against a fixed element of the furnace structure for tilting said electrode during the operation of the furnace.

In testimony whereof I have signed my name to this specification.

JONAS HERLENIUS.
